CLAIM

The ornamental design for a steering wheel lock storage device, as shown and described.

DESCRIPTION

FIG. 1 is a front, top and side perspective view of the steering wheel lock storage device embodying the design of the present invention;

FIG. 2 is an enlarged right end elevational view thereof;

FIG. 3 is an enlarged left side elevational view thereof;

FIG. 4 is an enlarged right side elevational view thereof;

FIG. 5 is an enlarged top plan view thereof;

FIG. 6 is an enlarged bottom plan view thereof;

FIG. 7 is an enlarged transverse sectional view thereof, taken along line 7—7 in FIG. 1, with the strap shown in an alternate position; and,

FIG. 8 is an enlarged left end elevational view thereof.
